UNITED STATES PATENT OFFICE.

GEORGE D. WHEELOCK, OF CLEVELAND, OHIO.

SASH-FASTENER.

937,348.

Specification of Letters Patent. Patented Oct. 19, 1909.

Application filed August 20, 1909. Serial No. 513,838.

To all whom it may concern:

Be it known that I, GEORGE D. WHEELOCK, a citizen of the United States, residing at Cleveland, in the county of Cuyahoga, State 5 of Ohio, have invented certain new and useful Improvements in Sash-Fasteners, of which the following is a specification.

This invention has for its object to provide a sash fastener that will be simple, but 10 effective, and one that cannot be operated from the outside.

A further object of the invention is to provide a means for automatically locking the window sash by the act of closing it 15 and without any further adjustment of the fastener; and with these and minor objects my invention consists of the parts and combination of parts as will be more fully hereinafter pointed out.

20 In the drawings Figure 1 is a top plan view of a sash fastener embodying my invention. Fig. 2 is a sectional view of the same on the line 2 2 Fig. 1. Fig. 3 is a similar view with the parts in unlocked position. Fig. 4 is an end elevation of the keeper and associated parts. Fig. 5 is an end view of the locking bolt and associated parts.

1 represents the keeper frame of any approved construction and provided with a 30 cut away portion 2 in its top wall.

3 is a drop latch pivoted at 4 in the keeper frame and provided with a seat 5 near its inner end in which is seated a coiled spring 35 6, the other end of the spring being seated on the under face of the top of the keeper frame around a lug 7. The outer end of the drop latch is provided with a lip 8 to be hereinafter referred to.

40 10 is the locking bolt frame, carried on the lower sash and provided with an elongated slot 11 in its top wall.

12 is the locking bolt, provided with a projecting end 13 extending through an opening in the front wall of the locking bolt frame. A spring 14 is coiled around the projecting end 13 and seated at one end against the locking bolt and at the other end against the front wall of the frame 12.

45 15 is a thumb screw secured in the locking bolt 12 and passing through the elongated slot in the top wall of the keeper frame. This thumb screw is adapted to be clamped down on the top of the frame 12 and thereby 55 lock the locking bolt either in an unlocked or a locked position, and it is also a means

by which the bolt may be moved or manually operated.

The inner end of the locking bolt is provided with a dovetailed slot 16 in which is 60 slidably mounted a locking slide 17 which is provided on its under face with a lug 18 which operates in the dovetail slot and limits the downward movement of the locking slide by engaging with the shoulder 19 formed in 65 said slot. The upper face of the locking slide 17 is provided with a rib 20 which is constructed to be engaged by the lip of the drop latch.

The operation is as follows: In Fig. 3 the 70 drop latch 3 is shown tipped to its lower position and the locking bolt is moved slightly backward. The parts are in this position just after the window sash has been closed and the drop latch is about to "wing" into 75 engagement with the slide 17. To go back a little farther in the operation, we will assume that the lower sash is being pulled down, carrying the locking bolt with it, this engages the drop latch tipping it until its 80 inner end strikes the upper wall of the keeper frame, as shown in Fig. 3. By a further movement of the sash the drop cams the locking bolt backward as shown in Fig. 3. The sash has now reached the end of its 85 movement, the spring 6 moves the drop latch on its pivot, which latch moves the slide 17 out of its way. The spring 14 forces the locking bolt forward until the lip on the drop latch engages the rib on the top 90 of the slide 17 whereupon the locking bolt is firmly locked. If it is desired to still further secure the locking bolt against movement the thumb screw 15 is screwed down 95 tight. In this manner the locking bolt may also be locked in its unlocked position.

Claims.

1. In a window sash lock the combination with a keeper, of a locking bolt and a slideable member on said bolt constructed to engage the keeper. 100

2. In a window sash lock the combination with a keeper of a slideable locking bolt, and a slideable member on said bolt constructed to engage the keeper and means to lock the locking bolt in its locked and unlocked position. 105

3. In a window sash fastener, the combination with a keeper and a drop latch pivotally mounted therein, of a locking bolt and a slideably mounted member on the bolt constructed to engage the drop latch. 110

4. In a window sash fastener, the combination with a drop latch, of a slideable bolt and a member slidably mounted on said bolt constructed to engage the drop latch.
5. In a window sash fastener, the combination with a drop latch of a locking bolt, and a member slidably mounted on said bolt constructed to engage the drop latch.
6. In a window sash fastener, the combination with a drop latch, of a locking bolt, and a member slidably mounted on said bolt and constructed to engage the drop latch, and means to lock the locking bolt in a locked or unlocked position.
- 15 7. In a window sash fastener, the combination with a drop latch, of a locking bolt, a spring to impel said bolt, a member slidably mounted on said bolt and constructed to engage the drop latch, and means to lock the bolt in its locked or unlocked position.
- 20 8. In a sash fastener, the combination with a keeper, a drop latch mounted therein, a spring to maintain said latch in a normal position, of a slideably mounted locking bolt,
- 25 a spring to keep said bolt in normal extended position, a member slidably mounted on said bolt and constructed to engage said drop latch.
9. In a sash fastener, the combination with a keeper frame, a drop latch pivotally mounted therein, a spring seated on said latch and bearing against said frame, of a locking bolt frame, a locking bolt slidably mounted therein, a shank extending from said bolt, a spring coiled around said shank, 30 a combined operating and locking member secured to said locking bolt, and a locking slide slidably mounted on said locking bolt and constructed to engage the said drop latch.
- 35 The foregoing specification signed at Cleveland O. this seventh day of October, 1908.

GEORGE D. WHEELOCK.

In presence of two witnesses—

LENA BECHTOLD,
JOSEPHINE KROECKEL.
